Application December 8, 1943, Serial No. 513,374

2 Claims. (Cl. 178—22)

1

This invention pertains to printing telegraph receivers and particularly to an apparatus for the reception of secret or confidential telegraph messages.

Signaling systems are desirable for naval, military, and civil purposes wherein it is required that messages be rendered unintelligible to persons unauthorized to receive them. Surreptitious interception of messages may be accomplished, for example, in the case of the wire communication by tapping signal wires, and in radio communication by means of receiving apparatus tuned to the proper frequency.

The primary object of the present invention is the provision of a simple, compact, and efficient apparatus for rendering messages unintelligible to unauthorized persons.

Another object of the invention is to provide a system or apparatus for precluding the unauthorized interception of intelligible messages by mechanical operation established in response to the respective control conditions.

A further object of the invention is to provide a deciphering instrumentality which is readily adaptable to commercially available printing telegraph apparatus.

Specifically, the apparatus according to the present invention is utilized to decipher and record previously enciphered messages which have been transmitted from a remote station. In order to encipher messages according to the present system, the elements of the code combinations of the original, intelligible message are combined with the elements of code combinations provided by a key tape or other control mechanism. In such arrangement, opposite conditions (that is, one element of the original code combination marking and the corresponding element of the key code combination spacing) produce a marking signal. Like conditions, however, with both elements marking or both elements spacing, produce spacing signals. This presumes, of course, that each of the elements of the respective code combinations are related to each other. That is, the No. 1 element of the original code combination is combined with the No. 1 element of the key code combination, and so forth. To take a specific illustration, let it be assumed that it is desired to encipher the character "R" which in the Baudot code is composed consecutively of spacing, marking, spacing, marking, and spacing conditions. Let it be further assumed that the key tape with which the particular enciphering operation is to be performed occupies a position whereat it is condi-

tioned for producing the letter "Y" combination, which in the Baudot code is composed consecutively of marking, spacing, marking, spacing, and marking conditions. Under the assumed

conditions, the enciphering operation would result in the production of an all marking or "Letters" combination, since in this particular illustration opposite conditions of all the related elements of "R" and "Y" code combinations are provided. This will be readily apparent from the following chart wherein the letter "M" indicates a marking condition and the letter "S" indicates a spacing condition:

15	1	2	3	4	5
Original Signal "R"	S	M	S	M	S
Key Signal "Y"	M	S	M	S	M
Enciphered Signal "Letters"	M	M	M	M	M

20 It is understood that both the transmitting and receiving end of a telegraph line will be equipped with identical key tapes which during message transmission will occupy identical positions. During transmission the key tapes are advanced between characters to modify the key signal, but both tapes occupy the same corresponding positions at all times. A station which receives enciphered signals is thus enabled to 25 decipher the unintelligible signals transmitted over the telegraph line by combining the enciphered signals with key signals provided by its key tape.

To illustrate a deciphering operation, the example given above in connection with the enciphering operation will be continued, and it will be assumed that a receiving station received the enciphered signal; namely, "Letters." The "Y" combination provided by the key tape at the receiving station can now be combined with the received "Letters" combination to decipher the enciphered signal to thereby reproduce the original signal "R," as clearly shown in the following chart:

45	1	2	3	4	5
Enciphered Signal "Letters"	M	M	M	M	M
Key Signal "Y"	M	S	M	S	M
Original Signal "R"	S	M	S	M	S

50 A more complete understanding of the invention may be had from the following description taken in conjunction with the accompanying drawings, wherein:

55 Fig. 1 is a front elevational view of the re-

ceiving printer embodying the deciphering device according to the present invention;

Fig. 2 is a plan view of the printer shown in Fig. 1;

Fig. 3 is a sectional view taken substantially on line 3—3 of Fig. 2;

Fig. 4 is a sectional view taken on line 4—4 of Fig. 3;

Fig. 5 is an enlarged fragmental view showing the essential elements of the deciphering device and

Fig. 6 is an electrical circuit diagram of a telegraph system embodying the present invention.

The deciphering mechanism according to the present invention is illustrated in the figures as applied to a type wheel printer of the type shown in copending application Serial No. 397,193, filed June 9, 1941, by W. J. Zenner. The printer framework is indicated at 11 and comprises side frames 12 and 13. Mounted on the side frames 12 and 13 are journal brackets 14 and 15 which support the main cam shaft 16. Also spanning the frames 12 and 13 is a plate 17, which carries a series of five electromagnets 19, 20, 21, 22, and 23 mounted on a bracket 24 and which constitutes part of the deciphering mechanism according to the present invention. Journalled in the side frames 12 and 13 and extending therebetween is a pivot shaft 25. Pivoted carried on the pivot shaft 25 substantially midway between the frames 12 and 13 is a printing arm 26 which carries at its extremity (the left end as viewed in Fig. 3) a platen member 27.

Platen member 27 cooperates with a type wheel segment 28 fixed to a type wheel shaft 29 journaled in a bearing 30 mounted in a plate 31 which spans the frames 12 and 13. The type segment 28 is provided with four rows of type faces; and a shift mechanism therefor is exemplified by a plurality of stop bars 33, provided for controlling the shifting movement of the type segment 28 to effect printing from the various rows of type. The bracket 34 is provided for guiding and supporting the tape between the platen 27 and the type segment 28. A spring 35 normally biases the type or printing arm 26 downwardly to hold the platen 27 free from the type segment 28. The printing operation is effectuated through the instrumentality of the vertical link 36 extending from the printing arm 26 and a printing cam (not shown) carried on the main shaft 16. Carried in brackets 37 (one of which is shown in Figs. 3 and 5) mounted on plate 17 is a pivot shaft 39 on which are pivotally carried a series of selector levers 41 to 45. Each of the levers 41 to 45 is provided with a cam follower projection 46 which cooperates with the periphery of an associated selector cam 47. There are five such cams 47, one associated with each of the five selector levers 41 to 45. The cams 47 are of similar cam contour but are displaced on the shaft 16 angularly so that the cam notches 48 are disposed in a helically arranged series whereby coaction with the cam followers 46 will occur in a sequential manner as the series of cams 47 rotates in synchronism with the speed of code impulsing. The levers 41 to 45 are normally biased in a clockwise direction about the pivot shaft 39 by individual springs 49.

The extremities 52 of the levers 41 to 45 cooperate with a shoulder 53 of an associated selector bar 54. Bars 54 are positioned vertically in the printer mechanism and are mounted on a shaft 55. Each of the bars 54 is provided with a slotted hole 56 cooperating with the shaft 55 so

that an individual spring 57 associated with each of the bars 54 tends to hold the bar 54 in its vertical position against the bottom of the slot 56. The vertical bars 54 are provided with a series of notches on one edge thereof and cooperate with a plurality of function bars 58 in the manner described in the copending Zenner application.

Juxtaposed to each of the selector levers 41 and 45 is a companion bar 59 which is slidably mounted with respect to its associated lever 41 to 45 on pivot shaft 39 and a stud 61 fixed to said associated lever. Each of the companion bars 59 is provided at its left-hand extremity (as viewed in Fig. 3) with a vertically projecting portion 71, and at its right end with a horizontally extending portion 72. Each of the bars 59 is normally biased rightwardly (as viewed in Fig. 3) by a spring 73 individual thereto, which extends between depending lugs on bar 59 and its associated levers 41 to 45.

Extremities 72 of each of the bars 59 cooperate with the armature 74 of each of the deciphering magnets 19 to 23. Armatures 74, when seized by their respective magnets 19 to 23, extend their individual springs 75, and thus permit springs 73 to urge or bias their respective bars 59 to the rightward position, as shown in Fig. 3. When the magnets 19 to 23 are de-energized, their individual springs 75 rotate the armatures 74 to their clockwise position, as shown in Fig. 5. Springs 75 are stronger than the springs 73, so that when the magnets 19 to 23 are de-energized, the springs 75, through armatures 74, will urge the bars 59 leftwardly against the action of biasing springs 73.

The vertically extending portions 71 of the bars 59 cooperate with the armature 76 of electromagnet 77. The magnet 77 is the single line magnet of the receiving selector mechanism and responds successively to the code signal impulses. The line magnet 77 is suitably mounted on a bracket 78. The armature 76 of magnet 77 is pivoted at 79, and a spring 81 normally tends to rotate the armature 76 in a clockwise direction about the pivot 79 when the magnet 77 is de-energized. An adjustable stop screw 82 is provided to limit the clockwise movement of the armature 76 so as to correspond to the leftward movement of the bars 59 by the armatures 74. As shown in Fig. 1, the lower extremity of armature 76 spans all of the projections 71.

As illustrated in Fig. 2, the cams 47 are carried on a sleeve 83 which is drivingly connected to shaft 16 by means of a friction clutch. Shaft 16 derives its power from a motor 84 through a pinion 85 and a gear 86. The cam assembly on shaft 16 also includes a cam 87 which acts upon a bell crank lever 88 to cause an extension 89 thereof to act upon all of the bars 54 to return them leftwardly to their normal unlatched position (as shown in Fig. 3), thus disengaging those members 54 which are engaged by the end 52 as will presently be described, and permitting them to be returned by their springs 57 to their upward normal position, with the shaft 55 at the bottom of the slot 56.

General operation

In the operation of the apparatus according to the present invention, it is assumed that the normal stop current on the line 91 (Fig. 6) is marking, in which condition the armature 76 will be seized, and the cam sleeve 83 on shaft 16 will be blocked against movement in well-known manner in start-stop operation. The electro-

magnets 19 to 23 are energized in accordance with code combinations of impulses impressed thereon under the supervision of a control mechanism. For example, a key tape 92 (Fig. 6) may be sensed by a record reader or tape sensing device to control the transmission of code combinations of signal impulses to the electromagnets 19 to 23. Upon receipt of the start impulse, which in the present illustration is a no-current impulse, the magnet 77 will be de-energized, thus releasing armature 76 which responds to the pull of the spring 81. This action initiates the rotation of the sleeve 33 in well-known manner. The cams 47 will then sequentially allow the levers 41 to 45 to respond to the pull of their respective springs 49 unless said levers are blocked through the coaction of portions 71 and armature 76. For example, assuming that the lever 43 (through projection 71) is not blocked, its cam follower portion 46 will fall into the depression in its respective cam 47 and lever 43 will be caused to rotate slightly in a clockwise direction. That is, if the lug 71 is not obstructed by the armature 76 when the portion 46 of lever 43 engages a cam notch 48, the lever 43 will be free to rotate clockwise to bring the end 52 thereof out of the path of shoulder 53 of lever 54 to permit the spring 57 thereof to rotate said lever 54 to bring the shoulder 53 under the extremity 52. Then, when the cam 47 rotates further to cause its high portion to urge the lever 43 counterclockwise, the bar 54 will be depressed against the action of its spring 57.

Under certain conditions of operation, in response to predetermined code signals, certain of the bars 54 will function to operate certain of the stop bars 33 to control the shift movement of the type wheel 28 to cause printing in a selected one of the four rows of type. This specific mechanism is fully described in said copending Zenner application.

Of course, if the projections 71 are blocked by the armature 76 no clockwise rotation of levers 41 to 45 will occur and, hence, the bars 54 associated therewith will not be operated downwardly. As previously described, cam 87 will act through ball 89 to disengage the operated bars 54 from the extremities 52 of the levers 41 to 45 with which they have become engaged, whereupon the respective bars 54 will be raised by their springs 57 to the position shown in Fig. 3.

In the operation of the deciphering arrangement according to the present invention, the levers 41 to 45 are controlled jointly by the selector electromagnet 77 and by the deciphering electromagnets 19 to 23. Having reference to Figs. 3 and 5, when the signal impulse received by the selector magnet 77 is of a marking nature, the magnet 77 will be energized and the armature 76 will be attracted, or moved to its position shown in Fig. 3, to bring its lower extremity into a position to cooperate with the lug 71 (of any one of the bars 59) when the bar 59 is in its rightward position. Under normal conditions of operation when the printer mechanism is employed for recording intelligible messages, the levers 41 to 45 are controlled solely by the selector magnet 77, so that clockwise rotation of the levers 41 to 45 sequentially under the control of cam 47 is controlled by the armature 76 such that when the armature 76 in its attracted position obstructs the projection 71 the cam follower 46 of levers 41 to 45 associated therewith will not fall into the notch 48 of the cam 47.

When the armature 76 is out of the path of the projection 71 the levers 41 to 45 will respond to the pull of their springs 49 and clockwise rotation will result to bring the extremity 52 of a lever 41 to 45 above the shoulder 53 of its associated bar 54, and in engagement therewith so that subsequent rotation of cam 47 will depress the arm 54 engaged with the levers 41 to 45.

10 However, under the control of the deciphering arrangement according to the present invention, the movement of levers 41 to 45 will be further governed by the deciphering device, exemplified by magnets 19 to 23, inclusive. In the 15 position illustrated in Fig. 3, the deciphering magnet 21 is shown energized under the control of the key tape 92, in which condition the armature 74 is attracted, whereupon the bar 59 is actuated by spring 73 to its rightward position to bring the vertically extending portion 71 below the line magnet armature 76, when said armature 76 is in the position shown in Fig. 3; that is, when the selector magnet 77 is energized and the armature 76 is seized. In this 20 condition of operation, the levers 41 to 45 (lever 43 in Fig. 3), through projection 71, will be blocked against operation under control of cams 47.

Having reference to Fig. 5, the four different 30 conditions of operations under the joint control of the deciphering magnets 19 to 23 and the selector magnet 77 will be described. The condition of operation shown in Fig. 3 is exemplified in Fig. 5 with the armatures 76 and 74 in their 35 dotted line positions. Under this condition of operation the lever 43 will not be permitted to rotate clockwise and hence its corresponding bar 54 will not be operated.

According to a second condition of operation 40 let it be assumed that the magnet 77 is energized by a marking impulse and that the deciphering magnet 21 is de-energized, so that armature 76 assumes its dotted line position and armature 74 assumes its solid line position in Fig. 5. Due 45 to this control, the bar 59 is actuated to its leftward position by reason of the fact that the spring 75 preponderates the weaker spring 73. Thus, the vertical projection 71 is moved out of 50 vertical alignment with the armature 76 so that upon rotation of cam 47 the lever 43 associated by the bar 59 (thus controlled), will be permitted to rotate clockwise when the cam notch 46 coincides with the cam follower projection 46. Under this condition of operation, the extremity 52 will be elevated to permit the shoulder 53 of bar 54 to be introduced therebeneath so 55 that when the high portion of the cam 47 actuates the lever 43 counterclockwise, the bar 54 will be urged downwardly.

Under a third condition of operation, it is assumed that the deciphering magnet 21 is de-energized, and that the bar 59 is maintained in its leftwise position by the stronger spring 75; 60 and further that the selector magnet 77 has been de-energized in response to a spacing signal, whereupon armature 76 is rotated clockwise (to its solid line position) by its spring 81 into engagement with stop 82 to bring the lower extremity of armature 76 into the path of the vertical portion 71. Thus, when cam 47 rotates, the cam follower projection 46 is prevented from falling into the notch 48 of the cam 47 due to 65 said engagement of portion 71 with armature 76. Hence, it is seen that when any of the de-

ciphering magnets 21 to 25 is conditioned in response to a spacing signal and the line magnet 77 is similarly conditioned, the resultant condition is a spacing condition; that is, levers 41 to 45 (lever 43 in this particular instance) are not operated in response to the rotation of cam 47.

Under a fourth condition of operation, the deciphering magnet 21 is energized, thus causing the armature 74 to be attracted to the dotted line position shown in Fig. 5, and thereby permitting the spring 73 to actuate the bar 59 to its rightward position bringing the vertical portion 71 to the dotted line position. Also, under this condition of operation the selector magnet 77 is de-energized in response to a spacing signal and armature 76 will assume the solid line position shown in Fig. 5. It will be observed, then, that the projection 71 is not blocked by the armature 76 since the armature is in the solid line position and the lug 71 is in the dotted line position in Fig. 5. Therefore, upon rotation of cam 47, the cam follower projection 46 will fall into the notch 48, thus imparting clockwise rotation to lever 43 (since projection 71 is not obstructed). Accordingly, the extremity 52 will be brought above the shoulder 53 and lever 54 will be biased inwardly by its spring 57 so that bar 54 will thereafter be operated under the control of cam 47.

With the mechanism just described it is seen that when the selector magnet 77 and deciphering magnet 21 (or any one of the deciphering magnets 19 to 23) assume the same conditions, namely, both marking or both spacing, the lever 43 operates as it would in response to a spacing signal if it were solely under the control of the selector magnet 77. On the other hand, if the selector magnet 77 and deciphering magnet 21 are operated in opposite manner, the lever 43 responds as it would for a marking signal if it were solely under the control of the selector magnet 77, which condition conforms to the tables presented hereinbefore.

Electrical circuit

In Fig. 6 is shown an electrical circuit or diagram of a system embodying the receiver according to the present invention. In the rectangle 101 is shown a set of transmitting contacts 102 such as are associated with a rotary cam distributor (or other type of distributor), and a series of contacts 103 which are controlled, in the present embodiment of the invention, by a key tape 104. It is, of course, understood that any other form of control mechanism for operating the contacts 103 is contemplated. It is noted that each of the contacts 103 is connected to a solenoid 105, and that the contacts 102 were included in a circuit extending from ground, through battery, then through the contacts 102 sequentially, over the line conductor 91, and through the winding of the selector magnet 77 to ground. Such a transmitter is disclosed in copending application Serial No. 496,552, filed July 29, 1943, by A. H. Reiber.

The magnet 77 is shown as included in a receiving station indicated by the rectangle 106, and the armature 76 and bars 59 are shown diagrammatically. Also shown associated with the bars 59 are the deciphering electromagnets 19 to 23, inclusive. Magnets 19 to 23 are included in a circuit extending from a common ground

wire to their respective contacts 107 governed by tape controlled levers 108, thence to grounded battery. It is understood that control mechanisms other than such as are controlled by tape may be employed in carrying out the present invention. The stepping of the tape is, of course, presumed to be effected cyclically in phase with the transmission and reception of code signals.

As previously mentioned, identical key tapes 104 and 92 (or identical control mechanisms of any other type) are provided at the transmitting and receiving stations 101 and 106, respectively. It is understood that these control mechanisms are placed in their respective station units in identical positions so that in the operation of the machine the transmitting apparatus contacts 102 and the selector magnet 77 shall have their selective operations altered in a uniform manner.

Although a specific embodiment of the invention has been disclosed, it is understood that the invention is not to be restricted to the structure herein described but is to be given an interpretation determined by the scope of the appended claims.

What is claimed is:

1. In a recorder, cam means, a plurality of instrumentalities carried on a common pivot and adapted to be operated in a predetermined manner by said cam means, signal controlled means, deciphering means, a corresponding plurality of elements carried on said pivot and dually controlled by said signal controlled means and said deciphering means for exercising control over said instrumentalities, each of said elements being slidably articulated to and in juxtaposition with an associated instrumentality, and selectable members operated by said instrumentalities according to the control exercised by said elements.
2. In combination, a selector including a plurality of cams, a follower associated with and urged into engagement with each of said cams, said cams having low portions for receiving the cam followers followed by raised portions for actuating the followers invariably, a pivot for supporting said followers, signal responsive means normally operable selectively to block the followers from engagement with the low portions of their cams, deciphering means, a corresponding plurality of elements carried on said pivot and dually controlled by said signal responsive means and said deciphering means for exercising control over said followers, each of said elements being slidably articulated to and in juxtaposition with an associated follower, and a slidable actuator associated with each follower for actuation thereby, said actuators operated by said followers according to the control exercised by said elements.

EMILY Y. REIBER,

Executrix Under the Last Will and Testament of
Albert H. Reiber, Deceased.
